(57) **CLAIM**

The ornamental design for a model vehicle body mount as shown and described.

DESCRIPTION

FIG. 1 is an upper, left, front perspective view of a model vehicle body mount showing our new design;

FIG. 2 is an upper, right, rear perspective view thereof;

FIG. 3 is a lower, right, front perspective view thereof;

FIG. 4 is a lower, left, rear perspective view thereof;

FIG. 5 is a front elevation view thereof;

FIG. 6 is a rear elevation view thereof;

FIG. 7 is a right-side elevation view thereof;

FIG. 8 is a left-side elevation view thereof;

FIG. 9 is an upper plan view thereof; and,

FIG. 10 is a lower plan view of the model vehicle body mount.

In the drawings, the broken lines illustrate portions of the model vehicle body mount that form no part of the claimed design.
